UNITED STATES PATENT OFFICE

164,455

GARMENT HANGER OR SIMILAR ARTICLE

Cis Silver, New York, N. Y.

Application May 20, 1949, Serial No. 2,763

Term of patent 3½ years

(Cl. D80—8)

To all whom it may concern:

Be it known that I, Cis Silver, a citizen of the United States of America, residing in New York, county of New York, and State of New York, have invented a new, original, and ornamental Design for a Garment Hanger or Similar Article, of which the following is a specification, reference being had to the accompanying drawing, forming part thereof.

Fig. 1 is a front view of a garment hanger or similar article, showing my new design.

Fig. 2 is a top plan view thereof.

Fig. 3 is a cross sectional view taken at 3—3.

Fig. 4 is a cross sectional view taken at 2—2.

The opposite side of Fig. 1 is substantially the same as shown. The dominant feature of my design resides in the portions shown in solid lines.

I claim:

The ornamental design for a garment hanger or similar article, substantially as shown and described.

CIS SILVER.
